REGULATING DEVICE FOR CLOCKWORK-OPERATED MECHANICAL FUSES FOR ARTILLERY PROJECTILES

Application filed May 26, 1927, Serial No. 194,271, and in Switzerland May 28, 1926.

Heretofore it has been proposed to employ a regulating device for clock work operated mechanical fuses for artillery projectiles comprising a cylindrical torsion spring in 5 the form of a spiral and arranged in such a manner that the axis of oscillation of said spiral coincides with the axis of the fuse and hence with the axis of rotation of the projectile during its trajectory. However, such 10 against disturbing influences of centrifugal force and against other physical influences produced by the rapid rotation of the projectile during its trajectory. However, such devices as hitherto known have proved unsatisfactory and therefore have been abandoned.

The unsatisfactory results of such devices are due to different causes, particularly to the following:

20 First of all and contrary to the assertions advanced, a spiral arranged in the axis of rotation of the projectile is forcibly subjected to the action of centrifugal force, particularly because of the great rotary speed 25 of modern artillery projectiles. In fact the centrifugal power tends to increase the extension of the spiral whilst it opposes its contraction, a feature which accounts for an enormous retardation in the running of clock 30 work movement, even in cases where corresponding tests had been made under apparently very good conditions, that is to say, even if a dead beat escapement without back-lash of the type to be described later 35 on has been employed.

It will also be understood that with such an arrangement of the spiral the enormous retardation in clock work movements, which has been stated to be as high as 100%, is 40 due to the irregular oscillations of the balance produced by centrifugal force, particularly in the case of a light nutation of the projectile.

Another reason which may account for the 45 failure of such known devices resides in the fact that the use of ordinary escapements makes it impossible to obtain sufficiently free oscillations of the balance and hence no oscillations of great amplitude.

50 Since in clock work operated fuses it is

necessary to make use of a very strong power spring in order to overcome the physical effects due to the rotation and to the nutation of the projectile, the power which the recoil escapement wheel has to overcome 55 during its stop intervals becomes too great for permitting it to impart to the balance oscillations of a great amplitude and to obtain the isochronism of these oscillations by means of a regulating spiral. 60

In the drawing Figure 1 is a partial longitudinal section illustrating one embodiment of my present invention.

Fig. 2 is a section on line II—II, Fig. 1,

Fig. 3 is a plan of the parts shown in Fig. 65 1 with certain elements removed for clearness of illustration,

Figs. 4 and 5 are plans of the split ring devices,

Fig. 6 is a central longitudinal section 70 illustrating the braking device,

Figs. 7 and 8 are respectively a partial plan and longitudinal section illustrating another form of dead beat escapement mechanism,

Figs. 9 and 10 are diagrammatic plans illustrating a third form of dead beat escapement mechanism, and

Figs. 11, 12 and 13 are diagrammatic plans illustrating still another form of dead 80 beat escapement mechanism.

From the drawing it is seen that the driving power derived from the power spring 1 is transmitted to the regulating device by means of a barrel shaft 2 to which is fixed 85 a crown wheel 3 fitted with internal teeth. This crown wheel is part of a gear train, the other members of which are the gears 4, 5, 6, 7, 8. The last gear of this train is an angle pinion 8 keyed on one end of a 90 small spindle mounted to rotate in a two part journal 9. In the middle of this spindle is keyed by means of a radial screw 10 a two part escapement wheel 11 of the type having alternating teeth provided with inclined impulse faces. This wheel cooperates 95 with a pallet 12 having the shape of a sector and fixed on a shaft or spindle 13 of the balance 14. The extent of the opening in this sector is between 180 and 200°. Im- 100

pulses are imparted alternately first in one direction and then in the other direction on both sides of the spindle 13 by the pressure exercised by the inclined faces of the 5 teeth, the two part wheel acting on the sector, and the stop is effected—without any back-lash of the escapement wheel 11—each time the point of one of the teeth of this wheel rests upon the top surface of the pallet 12.

10 The axis of the spindle 13 lies in the axis $x-y$ of the fuse and carries the balance 14. The balance preferably consists of two blades, one being a prolongation of the 15 other. Each one of these blades is made of a thin and flexible strip of metal and carries on its free end a small weight.

10 The portion of the housing of the clock work movement containing the regulator 20 preferably consists of two cross plates 15 which are spaced from one another by means of three pillars 16. This portion of the housing is fitted with slight friction, so that it may rotate freely around its own 25 axis, in circular grooves 17 provided therefor in the casing 18. This casing 18 is made of two semi-cylindrical parts. The upper plate 15 is made in the form of a drum in which is lodged the balance 14 and 30 the spiral spring 19 of the balance. The axis of the spring 19 is coincident with the axis $x-y$ which is the axis of the fuse and that of the projectile. At one end the spring 19 is fixed to a collet 20 mounted 35 on a half-flat shoulder 21 (Fig. 1) on the spindle 13. At its other end the spring 19 is connected to a split ring 22 whose angular position may be adjusted within a small cylindrical shoulder provided in the center 40 of a disk 23 which is fixed by means of four screws 24 in a circular notch in the cover 25 of the upper plate 15. The upper end of the spindle is journaled in this disk 23. In order to maintain the ring 22 in an ad- 45 justed position the points of the screws of an end pivot plate 26 screwed on the disk 23 are employed. The said ring 22 has a cylindrical projection on which a split ring 27 is frictionally mounted. The 50 ring 27 functions as a regulator in the following manner: The regulator ring 27 is provided on its inner surface with a small stud 28 through which the last or upper convolution of the spring 19 passes freely so 55 that whenever the regulator ring 27 is angularly displaced with regard to the ring 22, the working length of the spring 19 is ad- justed. In order to make this adjustment 60 the regulator ring 27 is toothed on its periphery and a circular opening 29 (Fig. 3) is provided in the disk 23 in order that a toothed driving key (not shown in the drawing) may be introduced. By this or equivalent means the regulator ring 27 may 65 be adjusted. The ring 22 and the regula-

70 tor ring 27 are fixed underneath the disk 23 in their axial direction by means of a washer 30 made of two parts and placed between the disk 23 and the cover 25. The convolutions of the spring 19 are preferably 75 of square section and are sufficiently close together to allow the spring to momentarily rest upon the balance 14 at the moment of firing during the inertia effect. 31 (Fig. 2) indicates an inertia pin of known type for 80 maintaining the balance in an initial position until the moment of firing the projectile.

85 The operation of this embodiment of the invention is as follows:

The fuse is mounted in the nose of the projectile in such a manner that its axis $x-y$ coincides with the axis of the latter and the balance 14 is locked until the moment of firing by means of the pin 31 which is automatically withdrawn by inertia at the moment the projectile is fired.

90 The relative position of the balance and the escapement wheel is adjusted in the course of manufacture by means of the split 95 ring 22 in such a manner that one of the teeth of the escapement wheel is normally in a position to cause it when released to give the first impulse to the balance, and the spiral 19 is also adjusted by means of the 100 regulator ring 27. As soon as the balance 14 is liberated the escapement wheel thus gives an impulse to the balance and thereafter is at rest without recoiling on itself during the whole duration of the oscillation 105 of said balance. At the end of this oscillation the tooth which determined the rest imparts in its turn a second impulse to the balance in the opposite direction and the adjacent tooth then arrives at its rest position, and so on.

110 If in the fuses provided with the type of regulator as described it is observed that the clock work goes too slowly and this appears to be due to the fact that the nutation 115 and the "precession" of the projectile hamper the regular operation of the balance, it is possible to eliminate or at least to considerably reduce these irregularities by submitting to the centrifugal force a movable 120 member which is in such a mechanical connection with the spindle 13 of the balance 125 that it exercises a slight braking action during the whole duration of the trajectory of the projectile, the braking action being proportional to the rotary speed of the projectile.

130 A device of this nature is illustrated in Fig. 6 in which the spindle 13 carries a pinion 32 which engages with a wheel 33 keyed on the small spindle 34 journaled in bearings provided therefor. The gears 32 and 33 might be replaced by bevel-gears. In such a structure the small spindle 34 would be arranged radially instead of being paral-

lel to the axis of the fuse. However, any suitable mechanism may be employed for braking the movement of the spindle 13.

Instead of the escapement as hereinbefore described any type of dead beat escapement might be made use of, in which the escapement wheel does not recoil on itself during the rest period.

For instance the dead beat escapement called "duplex" might be employed in which the escapement wheel is provided with two sets of teeth of different diameter, as shown in Figs. 7 and 8. In this structure the teeth of larger diameter serve for the non-recoiling rests and the teeth of smaller diameter for imparting the impulses.

A dead beat escapement of the "detent" type might also be used in which the rests are effected—without a back-lash or recoil of the escapement wheel—against a member termed "detent" entirely independently from the balance spindle, as shown in Figs. 9 and 10.

Finally a dead beat escapement called "detached anchor escapement" might be employed in which the lockings take place—also without any back-lash of the escapement wheel—against the lever of an anchor rigidly connected to an oscillating member called the "fork" transmitting the impulses to the balance, as shown in Figs. 11, 12 and 13.

I claim as my invention:

1. In a clock work operated mechanical fuse for artillery projectiles, a regulating device including a balance spindle, a balance carried thereby, a balance spring, a dead beat escapement permitting no back-lash in the balance, means for driving the escapement, and a rotary body mounted eccentrically to the axis of the balance spindle and associated therewith whereby the action of centrifugal force on the said rotary body produces a braking effect on the spindle and balance in proportion to the rotary speed of the projectile.

2. In a clock work operated mechanical fuse for artillery projectiles, a regulating device including a balance spindle, a balance carried thereby, a balance spring, a dead beat escapement permitting no back-lash in the balance, means for driving the escapement, a gear mounted eccentrically to the axis of the fuse and that of the balance spindle, and a gear carried by the balance spindle and meshing with the afore-said eccentrically mounted gear, the latter being subjected to the action of centrifugal force to produce a braking effect on the spindle and balance in proportion to the rotary speed of the projectile.

3. In a clock work operated mechanical fuse for artillery projectiles, a regulating device including a balance spindle, a balance carried thereby, a collet mounted on

the balance spindle, a split ring adjustable to position, a balance spring having one end thereof secured in the said collet and the other end in the said split ring, a second split ring associated with the first split ring and adjustable to position relatively thereto, means associated with the second split ring for controlling the oscillations of the outermost convolution of the said balance spring, and means for maintaining the split rings in their relative positions.

4. In a clock work operated mechanical fuse for artillery projectiles, a regulating device including a balance spindle, a balance carried thereby, a balance spring, a collet fixed on the balance spindle, a split ring, one end of the balance spring being secured in the collet and the other end in the split ring, the said split ring having a flange, a second split ring adjustable to position on the flange of the first split ring and having a projection within which the outermost convolution of the said balance spring passes, and means for securing the split rings in their relatively adjusted positions.

5. In a clock work operated mechanical fuse for artillery projectiles, a frame, a regulating device including a balance spindle, a balance carried thereby, a balance spring, a collet fixed on the balance spindle, a split ring, one end of the balance spring being secured in the collet and the other end in the split ring, the said split ring having a flange, a second split ring adjustably mounted on the flange of the first split ring and having a projection within which the outermost convolution of the said balance spring passes, the said second split ring being provided with a series of gear teeth for engagement with a key admitted through an opening in the frame to revolubly adjust the said second split ring to position, and means for securing the said split rings in their adjusted positions relatively to each other.

6. In a clock work operated mechanical fuse for artillery projectiles, a regulating device including a balance spindle, a balance carried thereby, a dead beat escapement, a collet mounted on the balance spindle, a split ring adjustable to position, a balance spring having one end thereof secured in the said collet and the other end in the said split ring, a second split ring associated with the first split ring and adjustable to position relatively thereto, means associated with the second split ring for controlling the oscillations of the outermost convolution of the said balance spring, and means for maintaining the split rings in their relative positions.

7. In a clock work operated mechanical fuse for artillery projectiles, a regulating device including a balance spindle, a balance carried thereby, a dead beat escape-

ment, a balance spring, a collet fixed on the balance spindle, a split ring, one end of the balance spring being secured in the collet and the other end in the split ring, the 5 said split ring having a flange, a second split ring adjustable to position on the flange of the first split ring and having a projection within which the outermost convolution of the said balance spring passes, and means for securing the split rings in 10 their relatively adjusted positions.

In testimony whereof I affix my signature.

ANDRÉ VARAUD.
